UNITED STATES PATENT OFFICE.

HOWARD SEVERN REGAR, OF NORRISTOWN, PENNSYLVANIA.

KNITTED HOSIERY.

Application filed June 21, 1922. Serial No. 570,017.

To all whom it may concern:

Be it known that I, HOWARD SEVERN REGAR, a citizen of the United States, residing at Norristown, in the county of Montgomery and State of Pennsylvania, have invented certain new and useful Improvements in Knitted Hosiery, of which the following is a specification.

My invention relates to knitted fabrics and more particularly to hosiery tops or legs which include a drop stitched section. The objects of the invention are to provide a method of manufacturing such tops by which tops are produced which include a complete plain ribbed stitch between the drop-stitched portions whereby in placing the tops upon the footer there will be the same number of stitches in the fabric as there are needles in the footer; to provide a method which will do away with the objectionable holes usually appearing at the junction of drop stitched portions with the foot; to provide a method which will produce a looped or arched drop stitch of greater elasticity and more attractive than the usual drop stitch; to provide a method by which tuck stitches and welts may be knitted through a complete plain stitch fabric instead of through a drop stitch fabric thereby producing a stronger and more durable fabric, and to produce an article embodying these features.

My invention consists in the various steps and combinations of steps which may be effected by a multiple bank machine such as described in my co-pending application Serial No. 570,018, filed June 21, 1922, to produce an article of manufacture herein-after described and claimed.

40 The drawing is a fragmentary enlarged view of a knitted fabric produced in accordance with my improved method.

In making hosiery tops on multiple bank machines in series with drop stitch effect produced by omission of needles, the entire series, including tucks, welts, clearing courses, etc., is affected by the lack of the full complement of needles, and plain courses cannot be made. The result is that, compared with tuck stitches, welts, etc., made with a full complement of needles, the tucks, welts, etc., are imperfect or incomplete. As used in this specification, the term complete will denote stitches or courses with the full usual complement of stitches such as would be made by a multiple bank circular ma-

chine with all the needles doing their work in the usual way, and the term incomplete will denote stitches or courses which are made by a like machine with needles omitted or are otherwise affected to drop a stitch. When stitches or courses are referred to but not designated as drop, or incomplete, complete courses will be meant.

Referring to the drawings, the numeral 1 indicates complete courses having the drop stitches, 2 incomplete courses having tuck stitches, 3 complete courses having double welt stitches, 4 complete courses having tuck stitches, 5 a loose course, 6 plain rib courses, 7 clearing courses, 8 a plain rib course, 9 complete courses having tuck stitches, 10 complete courses having double welt stitches, 11 plain rib courses, 12 complete courses having double tuck stitches, and 13 an incomplete course having single welt stitches.

I prefer to produce the drop stitch effect by means of a multiple bank machine having needles so constructed, positioned and guided that they will engage the yarn and pull it into loop form but shed the loop without forming a stitch, and when the end of a drop stitch section of the fabric is reached, these needles will be so positioned and guided that they will act as the other needles do and produce complete courses. A dropped-stitch so produced instead of being straight or unyielding to stretching, is loop or arch shape which makes the fabric more elastic and yielding whereby it is easier to apply or remove and better conforms to the shape of the leg. It also produces a more pleasing effect.

By providing complete plain courses so that there will be as many loops in the fabric as there are needles in the footer machine, the finished sock or stocking is made stronger, and objectionable holes between the top and the foot are eliminated.

The specific design disclosed in the drawing may be varied indefinitely without departing from the scope of my invention.

While I have described my invention as applied to hosiery tops, it may be employed in the manufacture of any knitted fabric in which dropped stitch effects are desired.

Having thus described my invention, what I claim as new and desire to secure by Letters Patent is:—

A method of making tubular fabric consisting in knitting complete courses having

looped drop stitches, then a welt of two courses, the tuck stitches of which immediately follow the drop stitch courses, then complete courses having tuck stitches, then

then a welt of two courses, then complete plain ribbed courses, then a welt of a single course, and then courses having looped drop 10 stitches.

5 a complete loose course, then complete plain ribbed courses, then complete plain clearing courses, then a complete plain ribbed course,

In testimony whereof I have signed my name to this specification.

HOWARD SEVERN REGAR.
